LOCKING CIRCUIT

George J. Maki, Elmhurst, Ill., assignor to Radio Corporation of America, a corporation of Delaware

Application August 24, 1940, Serial No. 354,033

4 Claims. (Cl. 178—52)

This invention relates to locking circuits and regenerating devices in both multiplex and simplex circuits.

The invention will be described in connection with a multiplex transmission circuit, but its application to multiplex receiving circuits or to simplex transmitting and receiving circuits will be apparent therefrom.

It is an object of my invention to provide a locking circuit that is simple and of lower cost than those heretofore in use.

Another object of the invention is to provide a locking circuit, operating without inertia, that requires only a single tube.

Another object is to provide a locking circuit consisting of a single gas tube of the two-electrode type.

Other objects of the invention will appear in the following description, reference being had to the drawing in which the single figure is a diagrammatic illustration of the improved locking circuit used for keying a transmitter in a multiplex telegraph circuit.

Referring to the drawing, reference character 1 diagrammatically illustrates a source of direct current potential across the terminals of which is placed a potentiometer resistance 2. A two-electrode gas tube 3, which by way of example may be a neon tube, is connected across points B and D of the potentiometer through a resistance 4. The positive high potential point A is connected to the marking contacts M of contactors I, II, III, such as are used in tape transmitters in multiplex transmission, there being three channels assumed in this particular illustration. The spacing contacts S are connected to the point C, which is negative in respect to the point A.

The movable contacts 5 of transmitter I are connected to contact 6 in the distributor 7 and the movable contacts 8 and 9 of the transmitters II and III are connected to contacts 10 and 11, respectively, in this distributor. The movable contact arm 12, which is rotated continuously as in the usual multiplex transmitter, is connected to the contact B.

The changing potential in resistance 4 is employed to operate tone keyer 13 and connections may be made for sending out tone frequency either for the marks or for the spaces, as desired. By way of example, I have shown the tone keyer 13 with the positive terminal of resistance 4 connected to unblock the push-pull tubes 14, 15 when a mark signal is transmitted, the negative terminal of the resistance 4 being connected

to the cathodes of tubes 14, 15 through a suitable negative bias 16. I have omitted the heaters for the unipotential cathodes, as they are well known in the art. This bias 16 is of such value as to block the push-pull tubes except when the positive potential from the marking impulse overcomes this negative bias.

The plate transformer 17 of tubes 14, 15 may be connected to a transmitter of any desired type. Since my invention, *per se*, does not relate to the transmitter, this has not been illustrated.

The action of my improved locking circuit takes advantage of the difference between the striking and extinguishing voltages of a gas-filled tube such as a neon tube, for example. Various characteristic values may be adopted, but merely by way of example I will say that I have obtained good results by using 135 volts at the source 1, with a 250,000 ohm resistor 4 in series with the neon tube. The contacts B and C may then be adjusted so that the voltage across AB is 16.5 volts and that across AC is 35 volts.

The operation of my invention will now be described.

Let it be supposed that channel No. 1 is sending a mark. Contactor I will thus be in engagement with marking contact M and the resistance between points A and B will be momentarily short-circuited. This will raise the voltage applied to the neon tube 3 to the striking point and it will conduct current. The potential drop in resistance 4 will then apply sufficient positive voltage to the input of the keying tubes 14, 15 to overcome the blocking negative bias 16 and the tone frequency of generator 18 will be applied to transformer 17 and sent to the transmitter (not illustrated).

When the distributor arm 12 leaves contact 6, neon tube 3 is not extinguished even though the short-circuit between points A and B has been removed. This is because the extinguishing voltage of the tube is considerably less than the striking voltage. Consequently, the tone current continues to be sent to the transmitter in the same way as disclosed in the more complicated locking circuit of Callahan Patent 2,086,351, June 6, 1937.

The marking condition established by channel No. 1 will continue until the distributor arm 12 engages a contact on the distributor 7 that has been connected to a spacing contact on the tape transmitter. Therefore, if the succeeding contact 10 has been connected to the marking contact by movable contact 8, no change takes place in keyer 13, but if keying lever 8 is moved to the

spacing contact in channel No. 2, when contact arm 12 engages contact 10, the resistance between points B and C will be short-circuited and this will reduce the voltage applied to the neon tube 3 to such a point that the tube is extinguished. In this situation, negative bias 16 blocks the push-pull keying tubes and tone frequency from generator 18 cannot pass to the transmitter. A spacing signal is therefore transmitted. This spacing signal will continue until the distributor arm 12 engages some contact that is set for a marking signal, which will momentarily short-circuit the resistance between the points A and B again and cause the neon tube to strike and send a marking signal.

It will be seen that my invention very materially simplifies the usual locking circuit, for example, the one described in the Callahan patent hereinbefore mentioned, in that only one two-element tube is required. This one tube performs the functions of locking circuits heretofore used.

Having described my invention, what I claim is:

1. In signalling circuits, a gas tube having an extinguishing voltage materially lower than its striking voltage, a voltage source consisting of a potentiometer resistance, a transmitter key having a mark contact connected to a high potential point in said resistance and a space contact connected to a lower potential point therein, said transmitter key having a switch tongue connected to an intermediate potential point in said resistance, said gas tube having one electrode connected to a point in said resistance that is negative in respect to said lower potential point, and a resistance connected between the other electrode of said tube and said intermediate potential point, said potential points being selected on the first-mentioned resistance so that said tube conducts when the tongue is on the mark contact and extinguishes when it is on the space contact.

2. In signalling circuits, a gas tube having an extinguishing voltage materially lower than its striking voltage, a voltage source consisting of a potentiometer resistance, a transmitter key having a mark contact connected to a high potential point in said resistance and a space contact connected to a lower potential point therein, said transmitter key having a switch tongue connected to an intermediate potential point in said

resistance, said gas tube having one electrode connected to a point in said resistance that is negative in respect to said lower potential point, a resistance connected between the other electrode of said tube and said intermediate potential point, said potential points being selected on the first-mentioned resistance so that said tube conducts when the tongue is on the mark contact and extinguishes when it is on the space contact,

5 10 and a utilization device connected to the last-mentioned resistance.

3. In signalling circuits, a gas tube having an extinguishing voltage materially lower than its striking voltage, a voltage source, a transmitter

15 key having one signal contact connected to a high potential point in said source and a second signal contact connected to a lower potential point therein, said transmitter key having a switch tongue connected to an intermediate potential

20 point in said source, said gas tube having one electrode connected to a point in said source that is negative in respect to said lower potential point, and the other electrode of said tube being connected to said intermediate potential point,

25 said potential points being selected on the voltage source so that tube conducts when the tongue is on the first contact, extinguishes when it is on the second contact and maintains its state as to conductivity when it is connected to neither of said contacts.

4. In signalling circuits, a gas tube having an extinguishing voltage materially lower than its striking voltage, a voltage source, a transmitter key having one signal contact connected to a

35 high potential point in said source and a second signal contact connected to a lower potential point therein, said transmitter key having a switch tongue connected to an intermediate potential point in said source, said gas tube hav-

40 ing one electrode connected to a point in said source that is negative in respect to said lower potential point, a signaling device connected between the other electrode of said tube and said intermediate potential point, said potential points being selected on the voltage source so that said tube conducts when the tongue is on the first contact, extinguishes when it is on the second contact and maintain its state as to conductivity when it is connected to neither of said contacts.
